DELIQUEFYING MEANS

Edwin L. Wiegand, Pittsburgh, Pa., assignor to
Orefraction Incorporated, Pittsburgh, Pa., a
corporation of Pennsylvania

Original application May 16, 1940, Serial No.
335,561. Divided and this application Decem-
ber 19, 1940, Serial No. 370,860

7 Claims. (Cl. 210—51)

This invention relates to means for de-liquefying slurry, that is, for reducing the liquid content of slurry. One use to which the invention may be put is for de-watering slurries in connection with apparatus in which the separation of material particles is accomplished by hydraulic counter-current settling, but the invention is not limited to such use. The principal object of the invention is to provide new and improved de-liquefying means of these types. This application is a division of my application Serial Number 335,561, filed May 16, 1940.

In the drawings accompanying this application, there is shown, for purposes of illustration, one form of apparatus embodying the invention and in which water is used for the purpose of separating material particles, and in these drawings:

Figure 1 is a side elevation of this illustrative form of apparatus, some of the parts being broken away,

Figure 2 is a side elevation, on a larger scale, of one of the hydraulic separating means forming part of the apparatus shown in Figure 1, parts being broken away,

Figure 3 is a side elevation, on a larger scale, of a de-watering means forming part of the apparatus shown in Figure 1,

Figure 4 is an end elevation of the discharge end of the de-watering means shown in Figure 3, parts being broken away,

Figure 5 is an elevation of the side of the de-watering means opposite from the side shown in Figure 3,

Figure 6 is a plan view of the de-watering means,

Figure 7 is an enlarged fragmentary detail sectional view, taken on the line 7—7 of Figure 8, and

Figure 8 is a fragmentary sectional view taken on the line 8—8 of Figure 7.

Referring to Figure 1, the apparatus there illustrated comprises, in general, two or more, in this instance three hydraulic separating means 10a, 10b, 10c, and one or more, in this instance two de-watering means 11a, 11b.

Each of the particular separating means forming part of the apparatus herein shown is designed to operate by that method of hydraulic counter-current separation commonly known as hindered settling, and such hydraulic separating means is disclosed and claimed in my application Serial Number 293,264, filed September 2, 1939.

The hydraulic separating means 10a includes a settling column 12 terminating in an upper

margin 13 over which the overage from the hydraulic separating means is adapted to be discharged into a launder 14. The launder 14 comprises a generally cylindrical body surrounding and spaced from the settling column 12 and an inclined bottom fastened water-tight to the settling column. The launder 14 is provided with a discharge spout 15 through which the overage is discharged.

10 Feed inlet means in the form of conduit means 16 is provided for feeding material to be separated to the separating column 12 of the hydraulic separating means.

At the lower end of the settling column 12 is 15 provided means for admitting water comprising a cylindrical jacket 17 within which is disposed a conical member 18 (see Figure 2) merging at its upper end with and joined water-tight to the separating column 12. Water may be supplied 20 to the space between the conical member 18 and the water jacket 17 by conduit means 19 in which may be interposed valve means (not shown). The conical member 18 is provided with a desired number of suitably circumferentially and axially 25 spaced holes 20 whereby water admitted to the water jacket 17 passes into the inside of the conical member 18 and provides an upward current of water subjecting the particles to be separated to hindered settling as is well understood in the 30 art.

The separating column 12 is fixedly supported by a plate 21 forming the bottom of the water jacket 17, the plate 21 being carried by supports 22 fragmentarily shown.

35 The underage of the separating means 10a passes down into a sump 23 provided with a discharge outlet 24. The sump 23 is connected to the separating means 10a by an extensible and contractible connection in the form of a suitable 40 metallic bellows 25, so that the sump 23 may move up and down with respect to a valve body 26 cooperating with a valve seat 27 provided on the sump 23. The valve body 26 is mounted on a stationary, adjustable rod 28. The rod 28 ex- 45 tends up through the separating means 10a, and through the conduit means 16, and is supported for longitudinal adjustment by the conduit means 16.

A beam 29, supported by a fulcrum 30, is provided with a weight 31 adjustable longitudinally 50 of the beam, at one side of the fulcrum 30, and at the other side of the fulcrum the beam engages the sump 23 through a suitable knife edge 32, so that the weight 31 tends to move the sump 23 upwardly whereas the weight of the underage in

the sump tends to move the sump downwardly. Consequently the rate of discharge of underage from the outlet 24 is adjusted automatically according to the weight of the undischarged underage.

The overage discharge spout 15 of the separating means 10a is connected to the feed conduit means 16 of the separating means 10b through the de-watering means 11a, and the overage discharge spout 15 of the separating means 10b is connected to the feed conduit means 16 of the separating means 10c through the de-watering means 11b, as will more fully appear.

The de-watering means 11a comprises a chamber 33 having a downwardly tapering lowering portion 34. Any suitable means (not shown) may be provided for supporting the de-watering means. In the embodiment illustrated the chamber 33 is generally cylindrical and the downwardly tapering lower portion 34 is formed by plane walls 35 intersecting the cylindrical wall of the chamber, so as to form a wedge-like lower portion which is closed at the bottom by a tubular member 36. The tubular member 36 is disposed at an angle with respect to the horizontal, about 30° in the illustrated embodiment, but this angle may be any suitable angle. The plane walls 35 are so constructed and arranged that their lower margins 37 abut the opposite longitudinal sides of the tubular member 36. The cylindrical wall of the chamber 33 has arcuate recesses, having margins 38, formed therein to accommodate the upper surface of the ends of the tubular member 36. The margins 37 and 38 are soldered, or otherwise suitably fastened water-tight to the tubular member 36.

The tubular member 36 has an aperture 39 in its upper portion, within the chamber 33, this aperture being here shown as formed by cutting away the upper semi-cylindrical half of the tubular member from a point 40 just within the lowest part of the cylindrical wall of the chamber 33 up to a point 41 about halfway up the tubular member 36, thus leaving the remaining lower half of the tubular member 36 in the form of a trough portion 42.

The discharge of material from the chamber 33 may be controlled by any suitable valve means. In this instance this control means comprises a gate 43 curved to fit the inside of the lowermost part of the cylindrical wall of the chamber 33, as may be best seen in Figure 8. The gate 43 is movable up and down and is held in position and guided by guides 44 suitably fastened to the inside of the cylindrical wall of the chamber 33. The lower margin of the gate 43 is formed with angled shoulders 45, and with an arcuate portion 46 adapted to fit the inside surface of the arcuate trough portion 42. A part of the arcuate portion 46 may be cut away so that when the gate 43 is in the position shown in Figure 7 a small passage 47 still is left.

The gate 43 is adjustable up and down by means of a rod 48 flattened at its lower end and suitably fastened to the gate. The upper end of the rod 48 is supported by a bracket 49 having apertured arms 50 through which the rod 48 is slideable, there being a knurled nut 51 disposed between the arms 50 and cooperating with a thread on the upper end of the rod 48, so that by turning the nut the gate 43 may be adjusted to the desired position. The bracket 49 is suitably mounted on the wall of the chamber 33. The end of the rod 48 may be provided with an indicator 52 cooperable with graduations 53 on the bracket 49.

Surrounding and spaced from the upper portion of the chamber 33 is a launder 54, braced by braces 60. The launder 54 has a discharge spout 55.

5 The upper end of the tubular member 36 of the de-watering means 11a is shown connected to the overage discharge spout 15 of the separating means 10a by a hose 56 (Figure 1) and the lower end of the tubular member 36 is shown connected to the feed conduit 16 of the separating means 10b by a hose 57. The de-watering means 11b is constructed the same as the de-watering means 11a, and the upper end of the tubular member 36 of the de-watering means 11b is shown connected to the overage discharge spout 15 of the separating means 10b by a hose 58 and the lower end of said tubular member is shown connected to the feed conduit 16 of the separating means 10c by a hose 59.

The operation of the apparatus is as follows. The particles to be separated are fed as a slurry of suitable wetness to the feed conduit 16 of the separating means 10a, the amount of water fed to the supply conduit 19 being regulated to the desired amount. Thereby the particles are subjected to hindered settling, a desired separation being secured. The particles which descend into the sump 23 constitute the underage and this underage is discharged at a rate dependent upon the weight of the undischarged underage in the sump 23. The particles which do not descend into the sump 23 are carried upwardly by the water current in the settling column 12 and are discharged into the launder 14. The overage discharged from the discharge spout 15 constitutes a slurry containing an undesired excess of water and when this slurry descends through the tubular member 36 and reaches the trough-like portion 42 excess water rises in the chamber 33 and is discharged over the upper margin of the chamber into the launder 54 from which it is discharged through the discharge spout 55.

It will be understood that the gate 43 is adjusted and set to suitably control the relation between the amount of upflow in the chamber 33 and the amount of flow downwardly in the trough 42 and through the opening left by the gate 43. The material discharged from the lower end of the tube 36 is a slurry de-watered to the desired extent, and this slurry is fed to the feed conduit 16 of the separating means 10b. In the separating means 10b the particles fed thereto are subjected to hindered settling separation as already described in connection with the separating means 10a, and the overage discharged from the spout 15 of the separating means 10b is fed to the de-watering means 11b and is de-watered as already described in connection with the de-watering means 11a, the de-watered slurry being then fed to the feed conduit 16 of the separating means 10c wherein the particles fed thereto are subjected to hindered settling separation.

65 The apparatus disclosed makes it possible to use a desired series of separating means 10a, 10b, 10c all of the same size. Also, the de-watering means 11b may be of the same size as the de-watering means 11a.

Once the apparatus has been adjusted, the flow of material through the series of alternate separating means and de-watering means is continuous and automatic.

70 From the foregoing it will be apparent to those skilled in the art that the illustrated embodiment of the invention provides new and improved de-liquefying means, and accordingly, accomplishes

the principal object of the invention. On the other hand, it also will be obvious to those skilled in the art that the illustrated embodiment of the invention may be variously changed and modified, or features thereof, singly or collectively, embodied in other combinations than those illustrated, without departing from the spirit of my invention, or sacrificing all of the advantages thereof, and that accordingly, the disclosure herein is illustrative only, and the invention is not limited thereto.

I claim:

1. De-liquefying apparatus, comprising: chamber means having an overflow outlet at an upper level and having a downwardly tapering lower portion having spaced approximately parallel lower margins extending from an upper level substantially below said overflow outlet downwardly at an angle to the horizontal; and wall means, providing a bottom for said spaced margins, including a tubular member joined to and extending along said margins, said tubular member extending at said angle upwardly beyond the upper level of said margins to provide an inlet portion, said tubular member having an aperture in its upper portion within said chamber means, and having a discharge outlet at its lower end for discharging de-liquefied slurry.

2. De-liquefying apparatus, comprising: chamber means having an overflow outlet at an upper level and having a downwardly tapering lower portion having spaced approximately parallel lower margins extending from an upper level substantially below said overflow outlet downwardly at an angle to the horizontal; and wall means, providing a bottom for said spaced margins, including a tubular member joined to and extending along said margins, said tubular member extending at an angle upwardly beyond the upper level of said margins to provide an inlet portion, said tubular member having an aperture in its upper portion within said chamber means, and having a discharge outlet at its lower end for discharging de-liquefied slurry, said aperture extending from approximately the lowest level of said margins to a level substantially below the highest level of said margins.

3. De-liquefying apparatus, comprising: chamber means having an overflow outlet at an upper level and having a downwardly tapering lower portion having spaced approximately parallel lower margins extending from an upper level substantially below said overflow outlet downwardly at an angle to the horizontal; wall means, providing a bottom for said spaced margins, including a tubular member joined to and extending along said margins, said tubular member extending at said angle upwardly beyond the upper level of said margins to provide an inlet portion, said tubular member having an aperture in its upper portion within said chamber means, and having a discharge outlet at its lower end for discharging de-liquefied slurry, said aperture extending from approximately the lowest level of said margins to a level substantially below the highest level of said margins; and valve means, for controlling the discharge from said discharge outlet, so constructed and arranged that the amount of said discharge may be adjusted in a range from a maximum discharge to a minimum discharge substantially greater than zero.

4. De-liquefying apparatus, comprising: chamber means having an overflow outlet at an upper level, and a downwardly tapering lower portion defining a dihedral angle; wall means providing

a bottom for said lower portion, said wall means being disposed at an angle to the horizontal and providing a continuously open discharge outlet, for de-liquefied slurry, from said chamber means at a level substantially below said overflow outlet, said overflow outlet and said discharge outlet being so constructed and arranged that the overflow from said overflow outlet is kept separate from the discharge from said discharge outlet; means for introducing into said chamber means, a stream of slurry to be de-liquefied, so constructed and arranged that said stream is approximately parallel to said bottom wall means and initially comes into upwardly exposed communication with the inside of said chamber means at a place adjacent said wall means at a level substantially higher than said discharge outlet but substantially below said overflow outlet and substantially below the highest level of said wall means; and said chamber means being constructed and arranged to provide a free, unobstructed path for flow of liquid from the upwardly exposed part of said stream to said overflow outlet.

5. De-liquefying apparatus, comprising: chamber means having an overflow outlet at an upper level, and a downwardly tapering lower portion defining a dihedral angle; wall means providing a bottom for said lower portion, said wall means being disposed at an angle to the horizontal and providing a continuously open discharge outlet, for de-liquefied slurry, from said chamber means at a level substantially below said overflow outlet, said overflow outlet and said discharge outlet being so constructed and arranged that the overflow from said overflow outlet is kept separate from the discharge from said discharge outlet; means for introducing into said chamber means, a stream of slurry to be de-liquefied, so constructed and arranged that said stream is approximately parallel to said bottom wall means and initially comes into upwardly exposed communication with the inside of said chamber means at a place adjacent said wall means at a level substantially higher than said discharge outlet but substantially below said overflow outlet and substantially below the highest level of said wall means; said chamber means being constructed and arranged to provide a free, unobstructed path for flow of liquid from the upwardly exposed part of said stream to said overflow outlet; and means for adjusting the size of said discharge outlet from a maximum to a minimum substantially greater than zero.

6. De-liquefying apparatus, comprising: chamber means having an overflow outlet at an upper level, and having substantially rectilinear bottom wall means disposed at an angle to the horizontal and providing a continuously open discharge outlet, for de-liquefied slurry, from said chamber means at a level substantially below said overflow outlet, said overflow outlet and said discharge outlet being so constructed and arranged that the overflow from said overflow outlet is kept separate from the discharge from said discharge outlet; means for introducing into said chamber means, a stream of slurry to be de-liquefied, so constructed and arranged that said stream is approximately parallel to said bottom wall means and initially comes into upwardly exposed communication with the inside of said chamber means at a place adjacent said bottom wall means at a level substantially higher than said discharge outlet but substantially below said overflow outlet and substantially below the highest level of said

bottom wall means; and said chamber means being constructed and arranged to provide a free, unobstructed path for flow of liquid from said exposed part of said stream to said overflow outlet.

7. De-liquefying apparatus, comprising: chamber means having an overflow outlet at an upper level, and having substantially rectilinear bottom wall means disposed at an angle to the horizontal and providing a continuously open discharge outlet, for de-liquefied slurry, from said chamber means at a level substantially below said overflow outlet; said overflow outlet and said discharge outlet being so constructed and arranged that the overflow from said overflow outlet is kept separate from the discharge from said discharge outlet; means for introducing into said chamber

means, a stream of slurry to be de-liquefied, so constructed and arranged that said stream is approximately parallel to said bottom wall means and initially comes into upward exposed communication with the inside of said chamber means

5 at a place adjacent said bottom wall means at a level substantially higher than said discharge outlet but substantially below said overflow outlet and approximately midway between the highest 10 level of said bottom wall means and the level of said discharge outlet; and said chamber means being constructed and arranged to provide a free, unobstructed path for flow of liquid from said exposed part of said stream to said overflow outlet.

EDWIN L. WIEGAND.
